UNITED STATES PATENT OFFICE.

WILLIAM C. SCHEU, OF GRAND JUNCTION, COLORADO, ASSIGNOR OF ONE-HALF TO
S. B. HAMPTON, OF CORONA, CALIFORNIA.

ORCHARD-HEATER.

1,148,803.

Specification of Letters Patent. Patented Aug. 3, 1915.

Application filed June 2, 1914. Serial No. 342,361.

To all whom it may concern:

Be it known that I, WILLIAM C. SCHEU, a citizen of the United States, residing at Grand Junction, in the county of Mesa and State of Colorado, have invented a new and useful Orchard-Heater, of which the following is a specification.

This invention relates to heaters for protection of orchards, etc., and the main object 10 of the invention is to provide a heater which will burn cheap fuel, such as crude oil, or distillate, with little or no smoke or smudge, and with substantially perfect combustion, so as to utilize the full heating capacity of the fuel.

Another object of my invention is to facilitate the ignition of the fuel.

A further object of the invention is to provide for indicating the level of the fuel 20 in the heater, to facilitate filling the fuel receptacle.

The accompanying drawings illustrate an embodiment of the invention, and referring thereto: Figure 1 is a side elevation of the heater. Fig. 2 is a section on line x^2-x^2 in Fig. 1. Fig. 3 is a section on line x^3-x^3 in Fig. 2. Fig. 4 is a perspective of the cover for the fuel receptacle, viewed from below. Figs. 5, 6, and 7 are broken side elevations 30 of modified forms of the stack for the heater. Figs. 8 and 9 are side elevations showing modifications of the stack. Figs. 10 to 13 are partial vertical sections showing further modifications.

The heater comprises a pot or fuel receptacle 1, a cover 2 therefor, and a stack 3 rising from the cover. The pot or fuel receptacle 1 may be of any suitable size and shape, and the cover 2 is preferably formed 40 so as to fit on the edge of the pot 1, forming a substantially tight joint. Cover 2 is preferably formed of frusto-conical shape and is provided at its center with an opening 2' having a raised rim on flange 4 on which the 45 stack 3 fits tightly.

The stack 3 is provided with lateral or side openings or perforations 5, and with deflector means adjacent to said openings, said deflector means being adapted to direct 50 the air entering said openings so that it enters the stack obliquely. These deflector means are preferably formed by bending or displacing outwardly the metal or material of the stack adjacent to and directly above

each opening, said openings being formed as 55 slits extending circumferentially of the stack, and said bent out metal portions being in the form of conical segments bulging from the stack, so as to extend obliquely outward and downward from the stack, 60 forming a louver or projection 6 over each opening. The opening with their deflectors may be arranged in circumferential rows around the stack, the openings in adjacent rows being in staggered relation, and one 65 or more of the rows of deflectors may be reversely arranged, as shown for the top row, in Figs. 1 and 3, and in that case an inclined ring 7 is preferably provided over such row of deflectors to act as a watershed 70 therefor. The perforated stack 3 may be of any suitable length, to provide for complete combustion, and may be used alone or may be provided with an upward extension 8, as shown in Fig. 1, extending to a sufficient 75 height to provide the required draft. The perforated part of the stack is preferably at a low level, as shown in Fig. 1, but, as shown in Fig. 8, the perforate stack portion 3 may be part way up the stack; or as shown 80 in Fig. 9, it may be at the top of the stack. In some cases all of the deflectors may be directed upward and outward, as shown in Fig. 9.

The heater is provided with an air-inlet 85 means, preferably in the cover 2, and consisting of an opening 10 in a raised portion 11 of the cover, and provided with a closure means 12, consisting of a plate pivotally mounted on said raised portion of the cover 90 and having suitable handle means 14. Below said raised portion of the cover a cup or receptacle 15 is provided, adapted to receive fuel for igniting the vapor generated in the main receptacle 1. Such raised portion of 95 the cover has an opening 17 extending over the cup or receptacle 15, to enable filling thereof, as well as ignition of the charge therein, said opening also preferably extending beyond the edge of the cup, so that 100 a portion of the fluid inserted therethrough will fall into the main receptacle, as herein-after set forth. The cup or receptacle 15 has outlet openings 18 communicating with the interior of the main receptacle 1, these 105 outlet openings being above the bottom of said receptacle, so that the lower portion of said receptacle is separate from the main

fuel receptacle 1 and is adapted to retain a body of fuel separate from and out of contact with the fuel in the main receptacle. Cover 2 is also preferably provided with 5 filling opening 20 having a closure means 21, formed as a plate pivoted on a raised portion 22 of the cover. Said closure means is provided with handle means 23 and may have a down-turned flange 24 at its outer 10 and rear edges, fitting against the wall 25 of said raised portion when the closure member is in closed position.

Means are provided for indicating in the receptacle 1, a definite level to which the 15 fuel is to be filled in the receptacle, said means consisting of a plate or member 28 attached to any suitable part of the heater, for example to the cover 2, and having a portion, such as a flange 29, extending horizontally at the level to which the fuel is to be filled, this indicating portion being so positioned adjacent to and below the filling opening 20 as to be visible through such opening. In case the stack opening of the 20 heater is used as the filling opening, the indicating means may be provided below the stack, as shown at 29' in Fig. 12.

The igniting cup 15 is preferably carried by the cover 2 and is preferably arranged 30 at such height, as shown in Fig. 3, that when the main receptacle is filled to the proper height, a portion of the oil or fuel will enter this igniting cup or receptacle. If desired, however, the igniting receptacle may be supported on the main receptacle 1, as shown at 35 15' in Fig. 11, and as shown at 15" in Fig. 10 it may be located above the level of the fuel in the main receptacle so as to require separate filling.

40 The receptacle 1 is filled with crude oil or other fuel, which may be poured in through the opening 20 until it just submerges the indicating member 29. By closing all the openings of the heater, the latter 45 may be protected from the weather, so as to be ready for operation at any time, the walls around the raised portions on the cover provided with the openings aforesaid, preventing water from running from the 50 cover into said openings.

The operation is as follows; assuming that the construction is as shown in Fig. 3. When the heater is to be started in operation, some easily ignited fuel, such as distillate, is poured through opening 17, so as to enter igniting cup 15 and also enter the main receptacle 1. This igniting fluid is ignited at the same time, and burns with the aid of the air entering through the air inlet 10, forming a pilot flame which passes through the outlet openings 18 over the body of fuel in the main receptacle and into the stack 3. At the same time combustion ensues in the main receptacle 1 over the 60 body of oil therein, sufficient to gradually 65

generate vapor, and when the vapor so generated rises into the stack 3 and meets the auxiliary air admitted through the openings or perforations 5 in the stack, it forms a combustible mixture with such air and this 70 mixture is ignited by the pilot flame from the igniting receptacle. The air inlet means in the cover 2 are so adjusted that the amount of air admitted to the main receptacle is substantially that which is required 75 for generation of vapor, and the main combustion does not ensue until the vapor enters the stack and is mixed with the auxiliary air therein. Under proper conditions of air supply I have found that the combustion proceeds in the perforated portion of the stack by a series of repeated explosions, the air and products of combustion being alternately drawn in and expelled 80 through the openings 5 in the stack, causing an effective mixture of the air with the vapor and resulting effective combustion of the fuel. Under these conditions substantially no smoke or smudge is produced, and the heat produced by the fuel is mainly developed at the perforated portion of the 85 stack, which is preferably at a low level, as stated, so that the heat is produced near the ground, where it is wanted.

In the case of the form of the invention 90 shown in Fig. 10 the operation is substantially as above described, except that the igniting cup is filled separately, in case a heavy fuel, for retarded combustion is desired therein; or this cup may be charged 95 only with the easily ignited fuel, at the time of starting the heater.

Various modifications may be made in the form and construction of the parts. For example, as shown in Fig. 5, the deflector 105 means coöperating with the openings in the stack may be formed as inclined annular flanges 31 on the stack 32, extending over the openings 34 in the stack. Or, as shown in Fig. 6, the deflectors 35 extend over a 110 vertically arranged row of openings 36 in the stack; or as in Fig. 7, a single deflector hood 37 may extend over all the openings 38, in the stack 39.

As shown in Fig. 13, the igniting cup, indicated at 15^a, may be so located as to discharge the igniting flame directly into the stack 41.

What I claim is:

1. In an orchard heater, a receptacle for fuel provided with air inlet means, a cover for said receptacle, and a stack mounted on said cover and opening at its bottom into the space at the top of the receptacle and directly below the cover, so as to form a combustion chamber at the lower part of said stack, in direct and free communication with the interior of the fuel receptacle, said stack being provided with perforations in its side wall, establishing direct communication 120 with the interior of the fuel receptacle, 125

cation from the outer air to said combustion chamber, and with deflector means extending obliquely downward and outward adjacent to said perforations.

5. 2. In an orchard heater, a receptacle for fuel provided with air inlet means, a cover for said receptacle, and a stack mounted on said cover, and opening at its lower end into the space at the top of the receptacle and 10 directly below the cover, so as to form a combustion chamber at the lower part of said stack, in direct and free communication with the interior of the fuel receptacle, said stack being provided with perforations in its side wall, establishing direct 15 communication from the outer air to said combustion chamber, and the wall of the stack being bent adjacent to each perforation, to form a deflector extending obliquely outward and downward.

3. In an orchard heater, a receptacle for fuel provided with air inlet means, a cover for said receptacle, and a stack mounted on said cover and opening at its lower end into the upper part of the receptacle, so as to 25 form a combustion chamber at the lower part of said stack, in direct and free communication with the interior of the fuel receptacle, said stack being provided with 30 perforations in its side wall, establishing direct communication from the outer air to said combustion chamber, and with an outwardly and downwardly extending deflector adjacent to each perforation.

35. 4. In an orchard heater, the combination of a main fuel receptacle, cover and stack means therefor, and a receptacle for igniting fuel having its lower portion separate from the main fuel receptacle, so as to retain a body of fuel separate from and out 40 of contact with the fuel in the main fuel receptacle, said cover means extending over said last named receptacle and being provided with an opening for filling and 45 ignition of fuel in said last named receptacle, and closure means for said opening.

5. In an orchard heater, the combination with the main fuel receptacle, of a receptacle for igniting fuel communicating with the main receptacle and having its lower portion separate from the main fuel receptacle to retain a body of fuel separate from and

out of contact with the fuel in the main fuel receptacle.

6. In an orchard heater, the combination 55 with the main fuel receptacle, of a receptacle for igniting fuel communicating with said main fuel receptacle and having its lower portion separate from the main fuel receptacle to retain a body of fuel separate 60 from and out of contact with the fuel in the main fuel receptacle, and means for admitting air to said receptacle for igniting fuel.

7. In an orchard heater, the combination 65 with a main fuel receptacle, provided with means for admission of air to produce partial combustion of the fuel and generation of vapor therefrom; of a receptacle for igniting fuel adapted to produce a flame in contact with the vapor generated in the 70 main receptacle, said receptacle for igniting fuel having its lower portion separate from the main fuel receptacle to retain a body of fuel out of contact with the fuel in the main receptacle.

8. In an orchard heater, the combination 75 with a fuel receptacle provided with a cover and stack, and with a filling opening in said cover, of an indicator supported in fixed position in said receptacle, and having a portion extending horizontally below and adjacent to said opening, to indicate the level to which the receptacle is to be filled.

9. As an article of manufacture, a stack 85 for orchard heaters having its lower end formed to fit on an orchard heater, having a plurality of circumferential rows of openings in its lower portion, formed as circumferential slits in its side wall, and said stack being provided with louvers over said openings, said louvers being formed by bulging out the portions of the stack wall directly over said openings to form outwardly and downwardly inclined deflectors, in continuous connection with the wall of the stack at 90 each side of said bulged out portions.

In testimony whereof I have hereunto set my hand, at Los Angeles, California, this 27th day of May 1914.

WILLIAM C. SCHEU.
